UNITED STATES PATENT OFFICE

156,256

DESIGN FOR A DISPLAY RACK FOR MERCANDISEJerome S. Kivett, Kansas City, Mo., assignor to Regal Plastic Co., Kansas City, Mo., a corporation of Missouri

Application June 7, 1948, Serial No. 146,796

Term of patent 3½ years

(CL. D80—9)

To all whom it may concern:

Be it known that I, Jerome S. Kivett, a citizen of the United States, residing at 6801 Locust, Kansas City, county of Jackson, and State of Missouri, have invented a new, original, and ornamental Design for a Display Rack for Merchandise, of which the following is a specification, reference being had to the accompanying drawing, forming a part thereof, wherein:

Fig. 1 is a perspective view of a display rack for merchandise, showing my new design.

Fig. 2 is a side elevational view thereof; and
Fig. 3 is a top plan view thereof.

I claim:

The ornamental design for a display rack for merchandise, as shown.

JEROME S. KIVETT.
